UNITED STATES PATENT OFFICE.

JOHN I. ARBOGAST, OF PITTSBURG, PENNSYLVANIA, ASSIGNOR OF ONE-HALF TO
HENRY L. COLLINS, OF PITTSBURG, PENNSYLVANIA.

METHOD OF MANUFACTURING GLASS CASE GOODS.

1,002,956.

Specification of Letters Patent. Patented Sept. 12, 1911.

Application filed July 16, 1910. Serial No. 572,258.

To all whom it may concern:

Be it known that I, JOHN I. ARBOGAST, a citizen of the United States of America, residing at S. S. Pittsburg, in the county of 5 Allegheny and State of Pennsylvania, have invented certain new and useful Improvements in Methods of Manufacturing Glass Case Goods, of which the following is a specification, reference being had therein to 10 the accompanying drawing.

This invention relates to a method of manufacturing glass shades similar to those shown and described in my companion applications #572,256, and 572,259, filed July 15, 1910, the present invention having special reference to that class of goods commonly styled "case" goods, wherein the article or ware produced has an interior finish of a different color from the exterior 20 finish, for instance, a green shade having a white lining or a white shade having a green covering.

Besides having the same objects in view as set forth in my companion application, 25 the present invention aims to expeditiously and economically produce a uniform piece of case goods that is above the standard of quality produced by skilled and expert laborers, yet produced by ordinary glass- 30 house labor.

The method and apparatus employed in connection with the present invention is similar in a great many respects to that disclosed in my companion application, but in 35 order that the production of a piece of case goods can be fully understood, reference will be had to the drawing, where there is illustrated means capable of carrying a method in accordance with this invention 40 into effect.

In the drawings: Figure 1 is a plan of the apparatus. Fig. 2 is a front elevation of the same, partly broken away and partly in section. Fig. 3 is a vertical sectional 45 view of a blow mold in accordance with the invention. Fig. 4 is an end view of the apparatus, and Fig. 5 is a vertical sectional view of a piece of case goods.

In carrying the method into effect, I utilize a suitable supply of air under pressure, 50 the air being carried beneath the stand 1 by a pipe 2 which is provided with a plurality of T's 3, said T's having valves 4 provided with vertical nipples 5. The valves are

normally retained in a closed position by 55 spring pressed valve stems 6, and said valves are adapted to be opened by a pressure of the foot against said stems. The stand 1 is slotted, as at 7, to accommodate interchangeable blow pipes 8 having the lower 60 ends thereof detachably mounted upon the nipples 5 and the upper ends thereof flared, as at 9. These pipes are designed for a machine and hand blowing, as will herein- 65 after appear.

Blanks are formed upon the flared ends 9 of the pipes 8, and to expedite the formation of the blanks a plurality of blow pipes are used in connection with the apparatus, and upon the stand 1 are arranged sectional 70 blank molds. The blank molds are identical in construction and each mold comprises base sections 10 and top sections 11, said sections having apertured lugs 13 by which said sections are pivotally mounted upon a post 75 14, carried by the stand 1. The base sections 10 have the confronting sides thereof recessed, as at 15, and cut away, as at 16, to provide clearance for the upper flared end of the blow pipe 8. When the base sections 80 10 are closed, the cavity of the mold formed by the recesses 15 is adapted to receive an initiatory mass of molten glass, which in its deposited form is designated 17. A pressure of air is then admitted to the pipe 8 to partially form a blank, which in its partially 85 formed position is designated 18. When air is admitted to the pipe 8 the glass is blown upwardly in the mold and carried away from the sides of the recesses 15. A secondary 90 mass or covering of molten glass, designated 19 is then deposited in the mold to cover the partially formed blank. The top sections 11 of the mold are then closed, these top sections having the confronting sides 95 thereof recessed, as at 20, to form a cavity that will communicate and register with the cavity of the top sections. Another pressure of air is then admitted to the pipe 8 and the partially formed blank is blown and completed, the blank adhering to the flared end 100 of the pipe and having an oblong formation, as shown in Fig. 3 of the drawings. The molds are then opened, the pipe 8 and the blank carried thereby removed from the 105 stand 1, the blank "warmed in," and then the pipe and blank are inverted and the blank placed in a blow mold. The blow mold

comprises two sections 21 having the confronting faces thereof recessed, as at 22, to form a cavity having the shape or contour of the piece of goods to be produced. As shown in Figs. 3 and 5 the cavity is shaped to produce a double shade, and after the blank is manually blown in the blow mold, the blow mold is opened and the piece of case goods, such as shown in Fig. 5 is produced.

In illustrating the piece of case goods from its inception to its completed form, I have exaggerated and aimed to distinctly show that two masses of glass are used in the formation of the blank and the completed piece of goods, but in reality these divisional lines are extinct, the blank being a homogeneous mass which when blown produces a piece of case goods having an interior finish of a different color than the exterior finish.

In using the term "case goods," I include all that class of ware and articles made of two or more differently colored masses of

vitreous material, one applied upon the other or one within the other.

25

What I claim is:—

A method of manufacturing glass case goods consisting in heating the outlet end of a blow pipe, then positioning the pipe with the heated end up into a core forming mold, then placing a batch of plastic glass within the mold and upon the heated end of the blow pipe to partially form a core, then placing a batch of another character of plastic glass within the mold and upon the first batch of glass, then forcing air through said pipe to form the two batches into a unitary core, then positioning the pipe with the core thereon into a blow mold, and then blowing through the pipe to complete the article.

40

In testimony whereof I affix my signature in the presence of two witnesses.

JOHN I. ARBOGAST.
